UNITED STATES PATENT OFFICE

PORTABLE FOLDING IRONING BOARD
ASSEMBLY

James Mack Morgan, Asheville, N. C.

Application June 10, 1947, Serial No. 753,681

2 Claims. (Cl. 38—114)

This invention relates to improvements in ironing board assemblies, and more particularly to an improved portable, folding ironing board assembly which may be carried from place to place and quickly set up for operation when desired.

It is among the objects of the invention to provide an improved portable, folding ironing board assembly which is easily folded to portable condition and unfolded to operative condition without attaching or detaching any parts, in which the ironing board is firmly and rigidly supported in operative condition and which is completely enclosed when in folded, portable condition, which is simple in construction, inexpensive and easy to manufacture, neat and attractive in appearance and which may be transported as a conventional article of personal luggage.

A somewhat more specific object resides in the provision of a portable, folding ironing board assembly comprising a foldable two-part casing, a two-part ironing board receivable in the casing when the assembly is folded, and pivoted strut and brace members permanently connecting the ironing board parts respectively to the casing part in a manner such that the ironing board is rigidly supported on the casing when the assembly is unfolded and folds automatically into the casing when the casing is closed.

Other objects and advantages will become apparent from a consideration of the following description in conjunction with the accompanying drawings, wherein:

Figure 1 is a side elevation of the ironing board assembly in unfolded, operative condition, a portion being broken away and shown in cross-section to better illustrate the construction thereof.

Figure 2 is a top plan view of the assembly illustrated in Figure 1.

Figure 3 is a transverse cross-section on a somewhat enlarged scale showing the assembly in partly folded condition; and

Figure 4 is a perspective view of the assembly in completely folded condition.

Referring to the drawing, the casing 10 is formed of two substantially identical open topped rectangular receptacles 11 and 12 arranged in end to end abutting relation and connected together at their abutting ends 17 by a hinge 21 for movement from the open position of Figures 1 and 2 to the closed position of Figure 4.

Positioned within and spaced longitudinally along receptacle 11 are two vertically disposed struts 22 having the adjacent one ends thereof pivotally connected to the bottom 16 of said

receptacle. A half section 14, of an ironing board, generally indicated by reference numeral 13, rests upon the other ends of the struts 22 and is pivotally connected at 26 thereto. The struts 5 22 may be of rectangular or U-shape if desired.

A second pair of vertically disposed struts 23 are positioned within and spaced longitudinally along the other receptacle 12 and the adjacent one ends thereof are pivotally connected by bearing caps 25 to the bottom 16 of the said receptacle 12. A second half section 15 of the ironing board 13 is arranged in end to end relation with respect to the first half section 14 and rests upon and is pivotally connected by bearing caps 26 to the other adjacent ends of struts 23.

A first brace 27 provided with a pivotal joint 28 intermediate its ends has one end pivotally connected to the pivotal connection of said one or lower end of the one of said first pair of struts 22 remote from the connected end of said receptacle 11. The other end of the brace is pivotally connected to the pivotal connection of the other or upper end of the one of said second pair of struts 23 remote from the connected end of said receptacle.

A second brace 29 provided with a pivotal joint 30 intermediate its ends is arranged in criss-cross relation to the first brace 27 and has one end connected to the pivotal connection of said other or upper end of said one of said first pair of struts remote from the connected end of said first receptacle 11. The other end of the brace is pivotally connected to the pivotal connection of said one or lower end of said second pair of struts 23 remote from the connected end of said receptacle.

In order to adjust the length of brace 27 and brace 29 arranged in criss-cross relation thereto, turnbuckles 32 are provided. It will be apparent that the adjustment of the braces would be such as to rigidly support the half sections 14 and 15 of the ironing board in close abutting end to end relation as shown in Figure 1.

There is thus provided a folding, portable ironing board assembly of light weight and neat appearance which may be conveniently and unobtrusively transported from place to place and which is brought to its fully operative condition by simply unfolding the opposite halves of the assembly about the connecting hinge.

The invention may be embodied in other specific forms without departing from the spirit or essential characteristics thereof. The present embodiments are, therefore, to be considered in all respects as illustrative and not restrictive, the

scope of the invention being indicated by the appended claims rather than by the foregoing description, and all changes which come within the meaning and range of equivalency of the claims are, therefore, intended to be embraced therein.

What I claim is:

1. A portable ironing board assembly comprising a pair of open topped receptacles arranged in end to end abutting relation and connected together for movement into and out of closing relation with respect to each other, a first pair of vertically disposed struts positioned within and spaced longitudinally along one of said receptacles and having the adjacent one ends pivotally connected to the bottom of said receptacle, a half section of an ironing board resting upon the other adjacent ends of said first pair of struts and pivotally connected to the latter, a second pair of vertically disposed struts positioned within and spaced longitudinally along the other of said receptacles and having the adjacent one ends pivotally connected to the bottom of said receptacle, a second half section of an ironing board arranged in end to end relation with respect to said first half section and resting upon and pivotally connected to the other adjacent ends of said second pair of struts, a first brace provided with a pivotal joint intermediate its ends and having one end pivotally connected to the pivotal connection of said one end of the one of said first pair of struts remote from the connected end of said receptacle and having its other end pivotally connected to the pivotal connection of said other end of the one of said second pair of struts remote from the connected end of said receptacle, and a second brace provided with a pivotal joint intermediate its ends arranged in criss-cross relation with respect to said first brace and having one end pivotally connected to the pivotal connection of said other end of the one of said first pair of struts remote from the connected end of said receptacle and having the other end pivotally connected to the pivotal connection of said one end of the one of said second pair of struts remote from the connected end of said receptacle.

2. A portable ironing board assembly comprising a pair of open topped receptacles arranged in end to end abutting relation and connected together for movement into and out of closing relation with respect to each other, a first pair of

vertically disposed struts positioned within and spaced longitudinally along one of said receptacles and having the adjacent one ends pivotally connected to the bottom of said receptacle, a half section of an ironing board resting upon the other adjacent ends of said first pair of struts and pivotally connected to the latter, a second pair of vertically disposed struts positioned within and spaced longitudinally along the other of said receptacles and having the adjacent one ends pivotally connected to the bottom of said receptacle, a second half section of an ironing board arranged in end to end relation with respect to said first half section and resting upon and pivotally connected to the other adjacent ends of said second pair of struts, a first brace provided with a pivotal joint intermediate its ends and having one end pivotally connected to the pivotal connection of said one end of the one of said first pair of struts remote from the connected end of said receptacle and having its other end pivotally connected to the pivotal connection of said other end of the one of said second pair of struts remote from the connected end of said receptacle, a second brace provided with a pivotal joint intermediate its ends arranged in criss-cross relation with respect to said first brace and having one end pivotally connected to the pivotal connection of said other end of the one of said first pair of struts remote from the connected end of said receptacle and having the other end pivotally connected to the pivotal connection of said one end of the one of said second pair of struts remote from the connected end of said receptacle, and length adjusting means on each of said braces.

JAMES MACK MORGAN.
